CLAIM

The ornamental design for a covered container with handle, as shown and described.

DESCRIPTION

FIG. 1 is a top, side and front perspective view of a covered container with handle showing the new design;

FIG. 2 is a front elevation view thereof, the rear elevation being a mirror image thereof;

FIG. 3 is a left side elevation view thereof;

FIG. 4 is a right side elevation view thereof;

FIG. 5 is a top plan view thereof; and,

FIG. 6 is a bottom plan view thereof.
